(57) **CLAIM**

The ornamental design of a wrench, substantially as shown and described.

DESCRIPTION

FIG. 1 is a perspective view of a wrench embodying the design of the present invention.

FIG. 2 is a top plan view of the wrench illustrated in FIG. 1.

FIG. 3 is a right side elevational view of the wrench illustrated in FIG. 1, with the left side elevational view being identical thereto.

FIG. 4 is a bottom plan view of the wrench illustrated in FIG. 1.

FIG. 5 is a front end view of the wrench illustrated in FIG. 1.

FIG. 6 is a rear end view of the wrench illustrated in FIG. 1.

FIG. 7 is a perspective view of a modified embodiment of the design shown in FIGS. 1-6.

FIG. 8 is a perspective view of a second modified embodiment of the design shown in FIGS. 1-6.

FIG. 9 is a top plan view of the wrench illustrated in FIG. 8.

FIG. 10 is a right side elevational view of the wrench illustrated in FIG. 8, with the left side elevational view being identical thereto.

FIG. 11 is a bottom plan view of the wrench illustrated in FIG. 8.

FIG. 12 is a front end view of the wrench illustrated in FIG. 8.

FIG. 13 is a rear end view of the wrench illustrated in FIG. 8; and,

FIG. 14 is a perspective view of a third modified embodiment of the design shown in FIGS. 1-6.
